UNITED STATES PATENT OFFICE.

FRED LICHTENBERG AND MICHAEL M. McCARTHY, OF YONKERS, NEW YORK.

BUILDING CONSTRUCTION.

1,410,932.

Specification of Letters Patent. Patented Mar. 28, 1922.

Application filed June 10, 1921. Serial No. 476,448.

To all whom it may concern:

Be it known that we, FRED LICHTENBERG and MICHAEL M. McCARTHY, citizens of the United States, and residents of Yonkers, 5 Westchester County, and State of New York, have invented certain new and useful Improvements in Building Constructions, of which the following is a specification.

This invention relates particularly to wall 10 constructions and the application of the trim for the doors, windows, baseboards and the like.

The objects of the invention are to construct the trim in complete units of such 15 form that they may be readily mounted and applied to the wall structure and be rigidly and permanently secured in place, so as to reinforce and become an integral part of the wall or building.

20 These objects are attained in our invention by means of certain novel features of construction, combination and relation of parts, as will appear in the course of the following specification, which is to be read 25 in conjunction with the accompanying drawings forming part thereof and wherein we have illustrated the invention embodied in some of its simplest and most practical forms.

30 Figure 1 in the drawings referred to is a broken perspective view of a wall constructed in accordance with our invention, and showing our special door, window and baseboard trim as in use.

35 Figure 2 is a vertical sectional view of the top of the window casing, on substantially the plane of line 2—2 of Figure 1.

Figure 3 is a similar sectional view of the 40 sill portion of the casing, substantially on the plane of line 3—3 of Figure 1.

Figure 4 is a horizontal sectional view of the side portion of the window frame, on substantially the plane of line 4—4 of Figure 1.

45 Figure 5 is a horizontal sectional view, illustrating the adjoining end portions of two of the slabs of which the wall is made.

Figure 6 is a sectional view of the door frame, on substantially the plane of line 50 6—6 of Figure 1.

Figure 7 is a vertical sectional view of the lower portion of an interior wall showing the baseboards applied thereto.

55 Figure 8 is a broken face view of the baseboard structure.

Figure 9 is a detail view showing the inside construction of the baseboard unit.

Figure 10 is a broken detail of a transom-bar construction, and

Figure 11 a section of same on line 11—11. 60 In constructing the wall, we preferably use the wall slabs disclosed in our co-pending application, Serial #411,163, consisting of pre-cast slab units of a suitable concrete or cementitious material such as we have indicated at 10 in Figure 5, arranged vertically in edge-to-edge relation, each having wire-netting reinforcements 11 therein, doubled over and protruding at one edge of the slab at 12, and having the free ends protruding from the opposite side of the slab at 13, the projecting folded reinforcement 12 at the edge of one slab being fitted between the projecting edges 13 on the adjoining slab, so as to in effect "mesh" the adja- 75 cent slabs together.

When the slabs are constructed with the corrugated or other air cell forming members 14, as in the application referred to, these air cell forming members are preferably inclined to the general flat plane of the slab, as we have indicated in Figure 5, so that they will overlap in the wall to provide a continuity of the air cell structure. 80

After the slabs have been set up in the 85 relation described, the joints between the slabs are completed by applying cement which is usually troweled on, as I have indicated at 15.

The door trim and the window trim are 90 usually applied as the wall is built up. In other words, the slabs are set up edge to edge until the point is reached where a window or door is to be located and then the door or window casing is abutted against 95 the last slab and other slabs are built on around such casing.

These casings are each formed hollow, usually of relatively thin but stiff sheet metal and they are secured in place by filling them with cementitious material which, as it hardens, reinforces and bonds the casing to the adjoining wall structure. 100

Considering first the window casing, it will be seen from Figures 2, 3 and 4 that the 105 same consists of a hollow shell 16 shaped to provide one or more internal shoulders or beads 17 and having edge flanges 18 spaced at the outer open side of the frame to fit over the edges of the adjoining slabs. In 110

setting up the frames, these edge flanges are usually secured together over the adjoining edges of the slabs by bolts or other suitable fastenings 19.

5 In the top of the frame (Figure 2), slots 20 are provided either at one or both sides of the wall to enable the bonding and reinforcing cement being poured into the frame. Thus after the frame is set up and the slabs 10 are positioned about the same, the cement in liquid form is poured in at the top of the casing so that it fills up the entire interior of the casing, as we have shown at 21, and overflows to a certain extent about the edges 15 so as to form a bond with the edge portions of the surrounding slabs, as we have indicated particularly at 22 in Figure 4. At this filling hardens, it will be seen that the casing is made practically solid and a unit with 20 the wall structure in which it is set.

If desired, jambs 23 of wood or the like may be set in the frame for the fastening of the hinges or other hardware, the hollow casing being for the purpose constructed 25 with a recess or pocket 24 to receive the jamb.

The door frame is constructed similarly to the window frame in that it is made up of a hollow shell 25, open at its outer edges and 30 shaped about its interior to provide a stop shoulder or flange 26. This frame may be secured in place in the same manner as the window frame, as by having bolts 27 passed through the edge flanges 28 and the intervening material of the slab over which the frame is fitted.

Along the top and at the outside or the inside or at both faces, the frame is provided with slots or openings 29 to receive the cementitious filling and bonding material 40 which is poured in after the door frame has been set in the wall and the slabs built up therearound.

The frames may be provided with suitable 45 inserts positioned to be embedded in the concrete, as indicated at 30 in Figure 6, to receive bolts or other fastenings for door hinges and the like and if desired, the frames may be shaped with pockets 31 to 50 receive felt or other packing strips 32.

The base board trim is also constructed as a hollow shell, as shown particularly at 33 in Figure 7, being given any desired ornamental configuration and having openings 34 in the top flanges thereof to receive the cement filling 35. This filling flows 55 along the interior of the baseboard, solidifying the same and bonding it to the slabs particularly at the joints between the slabs, it being evident from Figures 7 and 8 that the 60 filling material will flow out at such joints about the wire mesh on the adjoining edges of the slabs.

In the several forms of trim shown, we 65 have illustrated in each instance a shoulder

or shoulders 36 providing "grounds" for the plaster, stucco or other material.

The shell of the baseboard is shown as having a dependent flange 37 at the top and an upstanding flange 38 at the bottom there- 70 of to bear against the wall slabs and the inside view of the shell, Figure 9, shows how the pouring openings 34 are preferably ex- tended down into the upper flange, and how bonding openings 39 are provided in the 75 lower flange 38.

This invention, it will be seen, makes it possible to build up a wall or other structure very quickly out of standard stock units and the wall thus constructed becomes, by 80 the bonding and reinforcement of the parts, practically a solid unit.

The hollow frame members provide the complete trim, including lintels, sills, stools, aprons, jambs and stops and when filled with 85 the concrete, operate as solid reinforce- ments, bonding the various units of the structure.

It will be understood that the structure may be modified in various respects to meet 90 different building requirements. In the case of transom doors, for instance, the frame will be constructed to extend the full height from floor to ceiling, as we have indicated in Figure 10, so that when the frame is 95 filled with the solidified concrete, there will be two solid reinforced columns extending from floor to ceiling and tied together by the transom-bar 40 which being filled with concrete during the pouring operation acts 100 as a tie to hold the columns solidly together. These columns may be internally rein- forced, if desired, by means of suitable mesh fabric or rods, as indicated at 41, (Fig- 105 ure 11).

The window frames may be constructed with grooves containing packing strips similar to the doors, as indicated in Figures 2, 3 and 4. The strips or wooden in- 110 inserts 23 (Figures 2 and 4) may be placed inside the metal shells, as shown, or they may be seated in grooves at the outside of the shells, and we have shown in Figure 2 how grooves 42 may be formed along the upper edge of a frame to receive a pivot pin 115 on the upper end of a section of a double hinged door or window.

As many structural changes may be made within the scope of our invention, we wish it understood that the terms used herein 120 are employed in a description rather than in a limiting sense, except for such limitations as may be required by the prior art.

What we claim is:

1. In building construction, slabs ar- 125 ranged in adjoining relation to form a wall with openings therein and frames fitted in said wall openings and consisting each of a hollow metal shell closed at the interior of the frame and having spaced flanges about 130

- the exterior of the frame receiving between them the edge portions of the surrounding wall slabs, said flanges overlying and secured in contact with the opposite faces of the received slabs to thereby close the slab-receiving opening about the exterior of the frame and the thus closed frame having an opening or openings in the upper portion thereof for the admission of a liquid concrete which can be poured into the hollow frame to solidify the same and bond it to the surrounding wall slabs.
2. The structure of claim 1 in which the wall slabs are constructed with overlapping bonding means at the adjoining edges thereof which are entered within the hollow shell of the frame so that the filling also automatically effects the bonding together of adjacent slabs.
3. In building construction, slabs arranged in edge to edge relation and provided at their adjoining edges with overlapping bonding elements and building trim in the form of a hollow shell having an open side closed by the slabs and whereby the filling of cementitious material poured into said shell will be stopped by said slabs and by engagement with the overlapping bonding elements will bond the slabs together and to the trim, said hollow trim having an opening or openings in the upper portion of the same for the pouring in of the concrete in such liquid form.
4. In building construction, substantially flat slabs having cellular elements extending therethrough, inclined with respect to the general flat plane of the slabs and projecting beyond the edges thereof.
5. In building construction, substantially flat slabs having cellular elements extending therethrough, inclined with respect to the general flat plane of the slabs and projecting beyond the edges thereof and wire mesh reinforcements embedded in the slabs having lapped portions and spaced free ends at opposite edges of the slabs.

In witness whereof, we have hereunto set our hands this 6th day of June, 1921.

FRED LICHTENBERG.

MICHAEL M. McCARTHY.
